Primary Examiner — Patricia A Palasik*(74) Attorney, Agent, or Firm* — Scully Scott Murphy and Presser(57) **CLAIM**

The ornamental design for a flavor mixing machine, as shown and described.

DESCRIPTION

FIG. 1 illustrates a perspective view of a flavor mixing machine showing our new and ornamental design;

FIG. 2 illustrates a front elevation view thereof;

FIG. 3 illustrates a back elevation view thereof;

FIG. 4 illustrates a left side elevation view thereof;

FIG. 5 illustrates a right side elevation view thereof;

FIG. 6 illustrates top plan view thereof; and,

FIG. 7 illustrates a bottom plan view thereof.

The broken lines are included for the purpose of illustrating portions of the article that form no part of the claimed design.

1 Claim, 4 Drawing Sheets(56)
